CABINET HAVING ELEVATABLE TABLE TOP
AND RACKS

Ormond A. McKellar, Toronto, Ontario, Canada

Application July 9, 1945, Serial No. 603,956

8 Claims. (Cl. 312—151)

1

The present invention relates to cabinets of the top-opening type, wherein the top functions as table or work surface combining two utilities in the one article.

It has been heretofore proposed to combine such a cabinet with a mechanical cooling device to provide a domestic refrigerator. Accessibility was obtained by combining the shelves into a rack and making the rack vertically movable with respect to the cabinet. In this previously known device it was necessary to raise the entire contents in order to obtain access thereto. This was a heavy task and moreover exposed all the food articles and the interior of the cabinet to the relative warmth of the surrounding atmosphere. An additional objection resided in that cleaning the interior compartment was an onerous task involving the partial dismantlement, at least, of the refrigerator.

The object of this invention is to provide a top-opening type cabinet in which the objectionable features of previously known devices of the kind are overcome. A further object is to provide means for lifting the top without jamming.

These objects are achieved by providing means for selectively raising only the required food supporting rack, insulating means for closing the tops of the food racks individually, and an improved arrangement of tabletop lifting means.

The foregoing and additional features of the invention will hereinafter be more fully described in the specification and illustrated by way of example only in the annexed drawings wherein like numerals of reference refer to like parts throughout the various views and wherein:

Figure 1 is a side elevation with top in raised position and parts revealed by dotted lines or by broken-away portions of the structure;

Figure 2, an end view, with the top in raised position and parts shown in dotted lines or by broken-away portions of the structure;

Figure 3, a view of the cabinet with the top broken away, and showing the position of selector rods in dotted lines;

Figure 4, a fragmentary sectional view along a line 4—4 in Figure 3;

Figure 5, a fragmentary horizontal section on the line 5—5 in Figure 4;

Figure 6, a horizontal section of a portion of the lid viewed from above; and

Figure 7, a diagram of the elevating mechanism.

The cabinet 1 as shown is equipped with dual walls and the space intervening the walls is filled with a suitable insulant. A vertical partition 2,

2

suitably insulated, divides the interior of the cabinet into a cooling compartment 3 and a deep freezing compartment 4, although it will, of course, be readily understood that any number of compartments may be so constituted. The compartment 3 has disposed therewithin a rack 5 comprising a plurality of horizontal openwork wire shelves 6 vertically spaced and secured together and open on all sides, the said rack being entirely removable from the compartment. A block of insulating material 7 is secured to the upper end of the rack and has a centrally disposed perforated lug 8 secured thereto and projecting upwardly therefrom. Additional racks 5^a and 5^b similar to that hereinbefore described are similarly situated within the compartment 3, the racks 5, 5^a and 5^b, occupying the full area therein racks 5^a and 5^b being provided with perforated lugs 8^a and 8^b. It will thus be seen that when the said racks are in position in the cabinet, their combined tops, 7, 7^a and 7^b, form an insulated top wall for the compartment 3. Two additional racks, 7^c and 7^d, of like construction but varying in size are disposed within the compartment 4 having insulated tops 7^c and 7^d and perforated lugs 8^c and 8^d. In each case the upper surfaces of the insulated tops, 7, 7^a, 7^b, 7^c and 7^d, are flush with the top edges of the cabinet, and the perforations in the lugs 8, 8^a, 8^b, 8^c and 8^d have parallel axes.

Within the spaces intervening the dual walls there are mounted vertical compression cylinders 9, which are situated substantially midway between ends of said walls. These cylinders 9 are connected at their lower ends to a source of fluid under pressure by pipe line 9^a (see Figure 7).

There is also provided an insulated top closure member 10 for the cabinet 1, shown in the drawings to be of somewhat larger area than the said cabinet 3, and finished on its upper surface to function as a table or work surface. This top 10, comprises a framework and braces 33 of angle iron. Between the braces is provided insulating material. Bearing holes 33^a formed in the said angle iron braces, slidably sustain a plurality of selector rods 11, 11^a, 11^b, 11^c, 11^d, which are rectangular in section and so disposed relatively to the tops 7, 7^a, 7^b, 7^c, 7^d, that when the top 10 is in closed position one end of each selector may be pushed into an adjacent lug 8 in order that the said rack may thereby be removably and liftably engaged to the top 10. It will be found necessary as shown in the drawings to offset the selector rods 11^a and 11^c to bypass the racks 5^b

and 5^d. Offset portions 11^{ax} and 11^{cx} are shown in Figs. 3 and 6.

Handles 31 are provided for sliding the selector rods 11 in and out of engagement with the lugs 8. These handles are round in cross section and are slidably mounted in bearings 30 which are screwed to the underside of the top 10. Each handle is provided with a pin 32 extending transversely from one end and engaging in a slot in a collar 33 which is pinned to the end of a rod 11. Pin 31^a projects from handle 31 into T-slot 30^a in bearing 30. When handle 31 is pushed in pin 31^a slides in slot 30^a to the inner end thereof. The operator may then turn the handle moving the pin 31^a into the cross head of slot 30^a. To disengage the rack from the top a positive rotating movement of the handle as well as an outward pull is necessary, thus avoiding accidentally connecting or disconnecting the selector rods.

Piston rods 12, having piston heads 13, are rigidly fastened to the top 10, at each side thereof and substantially midway between its ends. While any source of fluid pressure may be utilized for actuating the pistons, Figure 7 shows a motor operated air compressor 14, an inlet valve 15, a pressure relief valve 16 and an eccentric valve selector or cam 17. The shaft 18 whereon the valve selector or cam 17 is rockably mounted may operate a power switch governing the compressor motor to turn the compressor on when inlet valve is opened and turn it off when pressure relief valve is opened. As shown in dotted lines in Figure 1, a lower lever 19 is fixed to the cam shaft 18. Lever 21 is secured to a spindle 23 journaled in the walls of the cabinet 1 and projecting to the exterior. A link 20 is pivotally attached by its ends to the lower and upper levers 19 and 21, and the handle 22 is rigidly fastened to the spindle 23.

To elevate the top 10, the handle 22 is pivoted in one direction, whereby the linkage formed by the members 18, 19, 20, 21 rocks the cam 17 to close the power connection to the compressor 14, to open the valve 15, thus admitting air under pressure to the cylinders 9. To lower the top 10 the handle 22 is pivoted in the alternate direction, the cam 17 thus opening the power switch and opening the relief valve 16 and permitting the inlet valve 15 to close. The weight of the said top 10 through the medium of the pistons forces the air out of the cylinders 9, and at a regulable rate through the valve 16.

The cabinet 1 is provided with a fully insulated bottom 24 (shown in dotted lines in Figure 1) beneath which the refrigerating mechanism and the compressor for the lifting mechanism are concealed, access being had thereto through a door 25 (Figure 1), in the lower portion of a wall. The cooling or evaporating coils are then placed in immediate contact with the interior set of the dual walls.

Amongst the numerous points of superiority are some it is particularly desired to stress. The positioning of the lifting cylinders, for example, is determined by a system of what might be called "triangulation." Placed as shown and described, jamming of the elevating apparatus because of disproportional weight distribution is avoided, since the load in any one rack of the cabinet is substantially equally divided between at least three of the elevators. The fourth elevator acts as a counterbalance for lifting the top. If the lifting cylinders were located at the corners

in many cases most of the load would be carried by one piston causing unbalance and jamming.

In further explanation of this theory of "triangulation" it is pointed out that no matter which rack is lifted, the weight is supported by the top at a point within a triangle of which three of the elevators form the corners. It should also be noted that the point at which the larger racks, 5^c and 5^d, are lifted is nearer the centre of the triangle so formed than the point at which the smaller racks, 5^a and 5^b are lifted. The point at which basket 5 is lifted is quite near the centre of a triangle formed by lines running between elevators 9 at one end and two sides of the refrigerator.

Furthermore, when it becomes necessary to clean or load a rack it may be raised from the interior confines of the cabinet, detached from its associated selector rod, and the lid of the cabinet closed until the said rack is ready for replacement. Moreover, when one of the racks is raised the insulators covering the remainder form a comparatively efficient heat seal over the un-evacuated space.

The cabinet hereinbefore described is, of course, not restricted solely to domestic food storage. It may be adapted and used with equal efficiency for quick freezing, for dehydration, or in fact for any purpose wherein a top-opening cabinet is recommended.

The invention thus having been fully described, it will be apparent that it permits of many alterations and modifications without departure from the spirit thereof, the scope of the protection contemplated will therefore appear from the following claims.

What I claim as my invention is:

1. In a cabinet having sides and a bottom forming an open-topped storage compartment therein, a plurality of vertically movable storage racks disposed in said compartment, the said racks having tops formed of heat insulating material normally closing the top of the compartment, a top closure member for said cabinet, means for lifting said top closure member, and means mounted on said top closure member for selectively engaging said racks to lift them above the top of the cabinet to provide access to said racks.

2. In a cabinet having sides and a bottom forming an open-topped storage compartment therein, a plurality of vertically movable storage racks disposed in said compartment, a lug projecting from each rack, selector rods, each selectively operable to engage one of the lugs, and means for simultaneously lifting all said selector rods to lift the racks with which they are in engagement, without lifting those racks not engaged by selector rods.

3. In a cabinet having sides and a bottom forming an open-topped storage compartment therein, a plurality of vertically movable storage racks disposed in said compartment, a lug projecting from each rack, selector rods, each selectively operable to engage one of the lugs, a top closure member for said cabinet on which the selector rods are mounted, and means for lifting the said top closure member to lift the selector rods and the racks with which they are connected.

4. In a cabinet having sides and a bottom forming an open-topped storage compartment therein, a plurality of vertically movable storage racks disposed in said compartment, a top closure member for said cabinet, means for lifting said top closure member, and means mounted on said top closure member for selectively engaging said

racks to lift them above the top of the cabinet to provide access to said racks.

5. In a cabinet having sides and a bottom forming an open-topped storage compartment therein, a plurality of vertically movable storage racks disposed in said compartment, lifting means comprising a projecting lug provided on each of the racks, a top closure member, bearings on the underside of the closure member, selector rods, each slidably journaled in one of the said bearings and adapted to engage one of the said lugs, and means for lifting the said top closure member.

6. In a cabinet having sides and a bottom forming an open-topped storage compartment therein, a plurality of vertically movable storage racks disposed in said compartment, lifting means comprising a projecting lug provided on each of the racks, a top closure member, bearings on the underside of the top closure member, selector rods slidably journaled in the said bearings, the interior ends of the said selector rods being each disposed adjacent to one of the lugs and adapted to engagement or disengagement therewith, and the exterior ends of said rods extending beyond the sides of the cabinet below the said top closure member for manipulation, and means for lifting the said top closure member.

7. In a cabinet having sides and a bottom forming an open-topped storage compartment therein, a plurality of vertically movable storage racks disposed in said compartment, lifting means comprising a projecting lug provided on each of the racks, a top closure member, bearings on the underside of the top closure member, selector rods slidably journaled in the said bearings, the interior ends of the said selector rods being each disposed adjacent to one of the lugs and adapted to engagement or disengagement therewith, and

the exterior ends of said rods extending beyond the sides of the cabinet below the said top closure member for manipulation, means for lifting the said top closure member, and handles for the selector rods engageable with and disengageable therefrom.

8. In a cabinet having sides and a bottom forming an open-topped storage compartment therein, a rectangular top closure member, a plurality of vertically movable storage racks in the storage compartment, means for selectively connecting and disconnecting the storage racks to the top closure member, and means for elevating and lowering the top closure member, said means comprising pistons secured to and depending from the top closure member substantially midway between the ends of each side of said member, cylinders in which said pistons are reciprocably mounted, secured to said cabinet, means for supplying fluid under pressure to the cylinders, and valve means controlling the admission of the fluid to the cylinders to raise and lower the top closure member.
